[57] CLAIM

The ornamental design for a protective cover for tra-
cheotomy tube, as shown and described.

DESCRIPTION

FIG. 1 is a perspective view of a protective cover for
tracheotomy tube, showing my new design, the broken
line showing is for illustrative purposes only and forms
no part of the claimed design;
FIG. 2 is a side elevational view thereof;
FIG. 3 is a bottom plan view thereof; and
FIG. 4 is a top plan view thereof.

FIG. 1

FIG. 2

FIG. 3

FIG. 4
